UNITED STATES PATENT OFFICE

FIORINDO BASSO, OF BALTIMORE, MARYLAND

NEEDLE HOLDER FOR SEWING MACHINES

Application filed March 22, 1932. Serial No. 600,521.

The present invention relates to a needle holder for sewing machines of the two or multiple needle type and has for its primary object to provide, in a manner as hereinafter set forth, a holder of this character embodying a novel construction, combination and arrangement of parts through the medium of which the needles may be independently and selectively shifted to inoperative position when desired.

Another very important object of the invention is to provide a needle holder for sewing machines embodying novel means for releasably securing the needles in operative or inoperative position.

Other objects of the invention are to provide a needle holder of the character described which will be simple in construction, strong, durable, efficient and reliable in use, which may be expeditiously installed on a conventional sewing machine, and which may be manufactured at low cost.

All of the foregoing and still further objects and advantages of the invention will become apparent from a study of the following specification, taken in connection with the accompanying drawing wherein like characters of reference designate correspond parts throughout the several views, and wherein:

Figure 1 is a view in side elevation of a needle holder constructed in accordance with the present invention, both of the needles being shown in operative position.

Figure 2 is a view in bottom plan of the holder.

Figure 3 is a view in vertical section, taken substantially on the line 3—3 of Figure 2, showing one of the slidable members in side elevation and in raised position.

Figure 4 is a view in bottom plan of the attaching and supporting member.

Figure 5 is an elevational view of the attaching and supporting member.

Figure 6 is a detail view in side elevation of one of the slidable members, together with the securing means therefor.

Referring now to the drawing in detail, it will be seen that the embodiment of the invention which has been illustrated com-

prises a supporting bar which is designated generally by the reference numeral 1, said supporting bar including a shank portion 2 for attachment to the sewing machine and a head portion 3.

The head 3 is formed to provide the vertical slideways 4 having vertical grooves 5 in the opposite side walls thereof. Elongated slides 6 are mounted for vertical movement in the slideways 4 and have formed thereon ribs 7 which are engaged in the grooves 5. Flanges 8 extend from the outer portions of the slides 6 adjacent the head 3. Extending into the slides 6 from the lower ends thereof are the sockets 9 for the reception of the needles 10.

Angular brackets 11 are rigidly secured by the screws 12 to the outer sides of the slides 6, the screws 12 projecting into the sockets 9 and constituting set screws for the needles 10. Spring-pressed detents 13 are operable slidably in chambers provided transversely therefor in the slides 6 and are engageable selectively in the sockets 14 provided therefor at vertically spaced points in the inner walls of the slideways 4. Opposed ears 15 rise from the brackets 11 and pivotally mounted therebetween for swinging movement in a vertical plane, as at 16, are the bifurcated bell crank levers 17 having their bifurcated ends straddling and operatively engaged with the detents 13. The other ends of the bell cranks 17 are provided with the concavo-convex thumb receiving portions 18. The free ends of the brackets 11 are provided with substantially similar finger receiving portions 19.

In use, the needles 10 are secured in operative position by engaging the detents 13 in the lowermost sockets 14. When it is desired to shift one of the needles to inoperative position, the detent 13 of the slide 6 in which said one needle is mounted is withdrawn from the lowermost socket through the medium of its respective bell crank lever 17 and the slide is raised through the medium of the bracket 11 mounted thereon until the detent engages in the uppermost socket 14. Thus, the slide is secured in raised position. A stop screw 20 is threaded into the lower end of

the head portion 3, the head of said screw 20 projecting into the slideways 4 and constituting a stop for arresting the downward movement of the slides 6.

5 It is believed that the many advantages of a needle holder for sewing machines constructed in accordance with the present invention will be readily understood, and although the preferred embodiment of the invention 10 is as illustrated and described, it is to be understood that changes in the details of construction and in the combination and arrangement of parts may be resorted to which will fall within the scope of the invention 15 as claimed. It is further understood that the device may be adapted to accommodate any desired number of needles.

What is claimed is:—

20 A needle holder for sewing machines comprising a supporting member attachable to the sewing machine and having a plurality of slideways therein, slides adjustably mounted in the slideways, said slides having sockets therein for the reception of the needles, the 25 inner walls of the slideways having vertically spaced sockets therein, the opposed walls of the slideways having grooves therein, ribs on the slides engaged in the grooves, brackets mounted on the slides, common means for securing the brackets and the needles on the 30 slides, spring-pressed detents slidably mounted in the slides and engageable selectively in the sockets for releasably securing the needles in operative or inoperative position, said detents including reduced portions, and bifurcated bell crank levers pivotally mounted on the brackets and operatively engaged with the detents for disengaging said detents from the sockets, the bifurcations of the bell crank 35 levers straddling the reduced portions of the 40 detents.

In testimony whereof I affix my signature.
FIORINDO BASSO.
